UNITED STATES PATENT OFFICE.

GEORGE E. PICKUP, OF NEWARK, OHIO, ASSIGNOR TO THE WEHRLE COMPANY, OF NEWARK, OHIO, A CORPORATION OF OHIO.

GAS BURNER.

Application filed July 5, 1924. Serial No. 724,237.

The invention pertains to gas burners of the type employed in open fire gas heaters; and the aim has been to produce a burner which is at the same time effectual in operation and capable of economical manufacture.

Gas burners of the character indicated have commonly employed a plurality of burner tips communicating with a common supply passage or manifold and having elongated discharge orifices formed by the use of a plurality of plates or strips secured together in uniformly spaced parallel relation; but difficulty is usually encountered in the provision of an effectual securing means due to the expansion and contraction of the parts under heat.

The object of the invention is to produce a gas burner having discharge tips or heads constructed so as to provide orifice-forming plates or strips properly arranged in uniformly spaced relation and in effect integrally united with the walls of the head so as to be effectually secured in position there-

in.

In the accompanying drawings, I have shown a burner of preferred form and while my invention will be hereinafter explained in a detailed description of this particular form, it is contemplated that various changes in the construction set forth may be made, by those skilled, without, however, departing from the spirit and scope of the invention as expressed in the appended claims.

Figure 1 of the drawings is a side elevational view of the burner.

Fig. 2 is a plan view thereof.

Fig. 3 is a fragmentary vertical sectional view on an enlarged scale through one end of the burner, the view being taken approximately on line of 3—3 of Fig. 2.

Fig. 4 is a plan view of a frame or form in which the jet plates are mounted so as to be capable of being supported in the mould in the operation of casting the burner.

Figs. 5 and 6 are respectively vertical sectional and side elevational views of such frame or form.

Fig. 7 is a plan view illustrating the method of casting the burner heads with the jet plates secured therein.

Fig. 8 is a fragmentary vertical sectional

view on an enlarged scale taken in the line 8—8 of Fig. 7.

The burner comprises a plurality of gas discharge tips or heads 10 communicating with a common gas supply passage or manifold 11. The latter in turn receives its supply of gas from an elongated tube 12 opening into the manifold centrally thereof and projecting in the present instance beyond one end of the manifold. At its projecting end the tube 12 has a bell mouth 13 into which the gas is discharged from the nozzle of a gas cock (not shown) in the usual way. On the opposite sides of the bell mouth 13 the supply tube 12 is shown as provided with lugs 14 whereby this end of the burner may be secured in the heater frame. The heads 10 at opposite ends of the manifold 11 are also shown as provided with forwardly projecting lugs 15, and one of the intermediate heads 10 has a rearwardly projecting lug 16, said lugs 15 and 16 serving to support the burner in the heater frame (not shown).

Each of the burner heads 10 comprises a main chamber 17 communicating with the interior of the manifold 11 by way of a passage 18 formed by a neck 19 which connects the head to the body of the manifold. From the chamber 17 the gas discharges through elongated jet orifices 20 formed by means of a plurality of plates or strips 21 extending transversely across the head and arranged in uniformly spaced parallel relation. Herein the head is shown as being rectangular in form, which is preferable because it lends itself readily to the formation of slots of uniform size, that is to say, equal in length as well as in width.

Because burners of this character are subject to intense heat, it is desirable that the plates 21 shall be made of some heat resisting metal such as the nickel chromium alloys and shall be firmly secured in the burner heads so as to avoid a loosening thereof under the expansion and contraction of the metal, and also it is desirable that the plates or strips be held in good heat-conducting relation to the body of the head so as to insure that the heat will be conducted from the plates to the head and thence down to the body of the main burner. To accomplish these results, I secure the jet plates in the head in the casting of the burner, the

opposite ends of the plates being permanently embedded in the metal of the head so as to make the plates in effect integral with the head.

5 Thus, preliminary to the moulding operation, I secure the jet plates 21 in a frame or form 22. This frame 22 is made of two U-shaped sections 22^a and 22^b of sheet metal which are secured together at their free edges 10 to form a rectangular tube. The opposite walls of the tube thus formed are provided with slots 23 therein adapted to receive projecting end portions 24 on the opposite ends of each of the plates (see Fig. 5). Said 15 projecting ends 24 are of a reduced width as compared to the width of the plates so as to form shoulders 25 abutting the inner sides of the tube. Also the said projecting ends are of a length substantially greater 20 than the thickness of the metal forming the tube for a purpose which will presently be apparent. The meeting edges of the two sections 22^a and 22^b may be secured together in any suitable way. That herein shown 25 consists of fingers 25 formed integral with the edges of one section and entered through slots 26 formed in the edges of the other section and then bent back against the wall of said other section as shown clearly in 30 Figs. 4, 5 and 6. The slotted edges of the section 22^a are shown as being offset as at 27 to receive the meeting edges of the other section and allow them to meet in the same plane.

35 Referring now to Figs. 7 and 8, A designates the lower section of a flask containing the base of a mould from which the burner pattern has been withdrawn and in which is placed a core B having head portions C, 40 adapted to produce the hollow burner body with the heads formed integral therewith. Each of the head portions C of the core is equipped with a frame 22 having jet plates secured therein as above set forth, 45 the lower end of the frame being slipped over the head portion C in each instance. As shown clearly in Fig. 8, the frame 22 is made of a length substantially greater than the internal depth of the head, and the upper portion of the frame projects into a 50 supporting recess C' formed by a suitable core-print on the burner pattern in the usual way. The lower edges of the jet plates are placed in contact with the upper faces 55 of the head portion C of the core, and the arrangement is such that the upper edges of said plates terminate in a plane substantially or slightly beyond the plane of the completed head to be formed.

60 It will be apparent that with the core thus equipped with plate-carrying forms or frames, the molten metal when introduced into the mould will flow around such frames and the projecting ends 24 of each of the 65 plates, passing as they do through and be-

yond the outer faces of the frame, become embedded in the metal of the head. Thus the plates become firmly and intimately united with the body of the head and the frame forms a lining for the side walls of the head. In the operation of finishing the burner thus cast, the projecting ends of the plate frames 22 are ground off together with the extreme outer edges of the plates so as to form a smooth slotted surface. 75

It will be observed that a burner constructed in accordance with my invention is of an advantageous character because of the uniting of the jet plates integrally with the body of the burner, thus insuring a maximum conduction of heat from the plates and heads and permitting the use of jet plates which will withstand heat better than cast iron or steel. The method of construction moreover insures that the plates will be 80 properly arranged in uniformly spaced relation and renders it possible to employ a metal in the plates different from that of the burner body. At the same time the amount of machine work required to finish 85 the burner is not materially greater than that required for finishing the ordinary body inasmuch as the inner walls of the slots, not being cast but rather formed from smooth finished plates, require no machining. Thus 90 the cost of manufacture is low. 95

I claim as my invention:

1. A gas burner comprising, in combination, a manifold having a plurality of burner heads cast integral therewith and a plurality of jet plates within each head arranged in uniformly spaced relation, said plates being made of a material different from the metal of the head and having their opposite ends permanently embedded in the 100 heads. 105

2. A gas burner head comprising a cast metal tubular member with a passageway therethrough, and a plurality of plates arranged side by side in parallel relation near one end of said passageway so as to form 110 jet orifices between them, said plates being made of material different from that of said member and having their opposite ends permanently embedded in the metal of said 115 member.

3. A gas burner comprising, in combination, a cast metal head providing a chamber communicating with a source of gas supply, a sheet metal lining in said head, and a 120 plurality of parallel plates forming jet orifices in said head, and having their ends extending through said lining and embedded in the metal of said head.

4. A gas burner comprising, in combination, a cast iron head having a chamber communicating with a source of gas supply, a sheet metal tubular member fitting within said head and providing a lining for the side walls of said chamber, and a plurality 125 130

of parallel jet plates having their opposite ends extending through said member into said head.

5. A gas burner comprising a casting having a supply passage and a head communicating with said passage, and a plurality of plates secured in the head in uniformly spaced parallel relation to form jet orifices, said head having a tubular member therein, and said plates having their opposite ends mounted in said member and serving to hold said member in said head. ¹⁰

In testimony whereof, I have hereunto affixed my signature.

GEORGE E. PICKUP.
